THERMAL PUMP

Filed June 8, 1940

tion shown in Fig. 1 is characterized by the provision of rigid walls which completely surround the movable parts of the pump. This is of particular advantage, since the pump is thus completely protected.

Fig. 2 shows a somewhat modified form of the invention. Numeral 11 denotes the heating tube connected to the pump. 17 is the condensation surface of the pump. To the rod 14 of the rocking lever system is secured the plate 22 which forms together with the resilient wall 21 the lower closure of the chamber 23. The rod 14 is also secured to the upper cover plate 25 of the working chamber 24 of the pump. Numeral 26 denotes a resilient wall and 27 the stationary bottom of the working chamber 24 to which are connected the suction conduit 28 and the pressure conduit 29.

Fig. 3 shows an absorption refrigerating apparatus of the continuous type provided with a pump 40, 41 designed according to the invention. This pump serves to circulate the strong solution. 31 is the generator of the absorption apparatus. The vapors developed in the generator 31 pass through a rectifier into the condenser 33, from where the liquified refrigerant flows through a throttle valve 34 into the evaporator 35 arranged in the cooling chamber. The vaporized refrigerant then passes from the evaporator 35 into the air-cooled absorber 36 through the conduit 43 and the conduit 39 wound around the part 41 of the pump. This part of the pump is thus additionally cooled by the cold refrigerant vapors. The conduit 42 serves to remove the liquid absorbent which might be entrained with the liquid refrigerant into the evaporator. Numerals 44 and 45 denote the conduits leading to the pump 40 and through which the strong solution is forced by the pump 40 through the heat exchanger 31 into the generator 31. The spent solution passes again through the conduit 46 and the float-operated valve 38 back into the absorber 36. The heated tube 48 of the part 41 of the pump extends into the heated passageway 47 of the generator 31. The pump is therefore heated by the waste gases of the generator.

The condensation surface of the part 41 of the pump is intensely cooled by the vaporous refrigerant flowing from the evaporator to the absorber. By suitably dimensioning the condensation surface the number of strokes of the pump may be varied in accordance with the quantity of vaporous refrigerant.

To create the desired pressure within the pump a suitable solution may be employed for use as an operating fluid.

What is claimed is:

1. A pump for circulating a working fluid comprising a sylphon-like body forming an internal working chamber for receiving such fluid, means forming a separate chamber superposed on said working chamber and containing an operating fluid, means for applying heat to a predetermined section of said separate chamber to evaporate part of said operating fluid therein whereby the pressure within said separate chamber is increased and said operating fluid is displaced downwardly away from the confined section affected by said heat applying means, the displacement of said operating fluid within said separate chamber removing it from contact with said heat applying means and causing subsequent cooling thereof and decrease in pressure in said separate chamber, interconnecting means between said chambers for causing said sylphon-like body and said working chamber formed

thereby alternately to contract and to expand responsive to the increase and decrease, respectively, of the pressure in said separate chamber, and valve means connected with said working chamber for expelling therefrom working fluid contained therein and for alternately admitting said working fluid thereto responsive to the alternate contraction and expansion thereof, respectively.

2. The device defined in claim 1, wherein said heat applying means is substantially constantly active during the operation of said pump.

3. The device defined in claim 1, together with means applied to said separate chamber from the outside thereof for effecting rapid cooling of the operating fluid therein subsequent to displacement thereof.

4. The device defined in claim 1, wherein said heat applying means is substantially constantly active during the operation of said pump, together with means applied to said separate chamber for effecting rapid cooling of the operating fluid therein subsequent to displacement thereof.

5. The device defined in claim 1, together with a displacer member disposed in said separate chamber and connected with said sylphon body for governing the displacement of the operating fluid therein in accordance with the movements of the displacer member.

6. The device defined in claim 1, together with a displacer member disposed in said separate chamber for governing the displacement of the operating fluid therein in accordance with the movements of the displacer member, and link means connecting said member with said sylphon body forming said working chamber to control the contraction and expansion operation thereof.

7. The device defined in claim 1, together with a displacer member disposed in said separate chamber for governing the displacement of the operating fluid therein in accordance with the movements of the displacer member, link means connecting said member with said sylphon body forming said working chamber to control the contraction and expansion operation thereof, and housing means for completely enclosing said working chamber and said link means.

8. The device defined in claim 1, together with a displacer member disposed in said separate chamber for governing the displacement of the operating fluid therein in accordance with the movements of the displacer member, link means connecting said member with the sylphon body forming said working chamber to control the contraction and expansion operation thereof, and housing means for completely enclosing said working chamber and said link means, said housing means being rigidly connected with the means forming said separate chamber and forming a unit therewith.

9. In a refrigerating apparatus of the class described, the combination of a heat operated refrigerant generator and an evaporator and absorber for receiving said refrigerant, with a heat operated pump for circulating strong solution between said absorber and said generator, said pump comprising means forming a pumping chamber for said strong solution, means forming a separate control chamber containing an operating fluid, common heat producing means for said generator and for heating the operating fluid in said control chamber, said operating fluid being displaced within said control chamber and the pressure therein being increased responsive to such heat-

ing, cooling means for said control chamber for subsequently cooling said operating fluid to reduce the pressure therein, means responsive to the pressure fluctuations in said control chamber for causing the strong solution in said pumping chamber to circulate, and means for circulating through said cooling means refrigerant flowing from the evaporator to the absorber.

10. The combination and structure defined in claim 9, wherein two plates separated by bellows-like side walls constitute the means forming the pumping chamber, and wherein the pressure fluctuations in said control chamber alternately contract and expand said pumping chamber to circulate the strong solution therein through the medium of valve means connected thereto.

11. The combination and structure defined in claim 9, together with means in said control chamber for governing the displacement of the operating fluid therein responsive to alternate heating and cooling thereof, and means linking said last named means with said pumping chamber for controlling said displacement in accordance with the pumping action thereof.

12. The combination and structure defined in claim 9, wherein two plates separated by bellows-like side walls constitute the means forming the pumping chamber, together with means in said control chamber for governing the displacement of the operating fluid therein responsive to alternate heating and cooling thereof, link means connecting said last named means with said pumping chamber for controlling said displacement in accordance with the pumping action thereof, and housing means completely enclosing said link means and said pumping chamber.

13. A pump device of the class described comprising a fluid containing valve-controlled sylphon body forming a pumping element for the fluid contained therein, means forming a sealed liquid containing chamber, means for applying heat to said chamber at a point above the liquid surface therein to cause evaporation confined within said chamber of part of said liquid from

the surface thereof and consequent increase of pressure in said chamber and downward compression displacement of the liquid surface therein away from said heat applying means whereby said displaced liquid is cooled again by contact with the wall of said chamber remote from said heat applying means to reduce the pressure in said chamber and allow upward return expansion of the liquid, and means for transmitting the alternate compression and expansion displacement of said liquid in said chamber to said pumping element.

14. The pump device defined in claim 13, together with a displacer member in said chamber for controlling the displacement of the liquid therein, said member being connected with said sylphon body and moving within said liquid upwardly during the downward compression and downwardly during the upward expansion of the sylphon body.

15. The pump device defined in claim 13, together with a displacer member in said chamber for controlling the displacement of the liquid therein, said member being connected with said sylphon body and moving within said liquid upwardly during the downward compression and downwardly during the upward expansion of the sylphon body, and link means connecting said displacer member with said pumping element.

16. The pump device defined in claim 13, together with a sylphon-like extension on said chamber which is alternately expanded and contracted responsive to compression and expansion displacement of the liquid therein, and means connecting said sylphon-like extension with said pumping element constituting the means for transmitting the alternate displacement of said liquid thereto.

17. The pump device defined in claim 13, together with means for cooling the wall of said chamber disposed at a point remote from said heat applying means.
